R. E. REARDON

EDUCATIVE DUMMY FIREARM

Filed April 5, 1922

UNITED STATES PATENT OFFICE.

ROBERT E. REARDON, OF WRIGHTSVILLE, PENNSYLVANIA.

EDUCATIVE DUMMY FIREARM.

Application filed April 5, 1922. Serial No. 549,944.

To all whom it may concern:

Be it known that I, ROBERT EDWIN REARDON, a subject of the King of Great Britain, residing in the borough of Wrightsville, 5 county of York, and State of Pennsylvania, United States of America, have invented new and useful Improvements in Educative Dummy Firearms, of which the following is a specification.

10 My invention relates to improvements in educative dummy firearms and the object is to provide a simple, low priced, safe but very realistic and instructive means for target practice, which may be used anywhere.

15 My improvement is herein presented in the form of a repeating practice target rod pistol which may be loaded with a roll of paper caps such as used in toy pistols, with means for automatically feeding the caps 20 towards an anvil and exploding a cap coincidentally with the hammer blow which impels the target rod forward through the barrel and against an aim recording target. Broadly, I present a device combining accurate target marking means with simultaneously acting means for giving the explosive effect to each shot. It is obvious that if no explosive effect is desired the sounding element may be dispensed with as not essential 25 to an operation of the target marking means. I attain the objects of my invention by the construction, combination and arrangement of parts hereinafter described and particularly pointed out in the claims, it being 30 understood that I do not intend to limit myself to the details of construction or combination of the various parts.

My invention is illustrated in the accompanying drawing in which:

40 Figure 1 is a side elevation of my target practice educator pistol showing in full line through the cap-loading side opening, and otherwise by dotted lines, the various parts in their respective normal positions.

45 Figure 2 is a front illustration showing the form of target and target holder preferably used with my pistol.

In the drawings like numerals refer to similar parts.

50 The stock portion, A, of the pistol is preferably cast, metal with a barrel portion, B, made of tubing for greater accuracy, suitably secured therein. A side opening plate, C, turning on pivot C¹, allows the

stock, A, to be opened for loading with the 55 sound producing element, in this case a strip roll, T and T¹ of paper explosive caps.

The barrel, B, has mounted thereon a target marking rod E, with retracting spring, D, pointed head, F, with rubber point-hood, 60 J, and butt piece, G. A front sight piece, I, mounted in the forward end of the barrel, B, provides a bushing, I, through which the rod, E, may slidingly move in the barrel axis. A rear sight, H, is mounted on the 65 breech end of the barrel, B. A hammer, K, with a rod impelling head, K¹, and a sound producing head, K² and a radial flange, or tail, K³, is pivotally mounted on a stud, A¹, in the pistol stock, A, and is maintained in 70 normal position, with the sounder head, K², against an anvil wall, A⁴, in the pistol stock, A, by means of a spring, N, mounted on studs, A² and A³, to bear against said tail flange, K³, of the hammer K. Pivotally 75 mounted by insertion of its head L¹, in a recess, K⁴, of the hammer, K, is a strut L, which is normally extended by means of a spring, M, mounted in its head, L¹. A trigger member, Q, is pivotally mounted on a 80 stud, A⁵, in the pistol stock, A, and held in normal, retracted position by means of a spring, U, mounted on said stud, A⁵, and bearing at one end on the upper side of a lateral wall extension, Q¹, of the trigger 85 member, Q, and at its other end bearing on a stud, A⁶, in the pistol stock, A. The trigger member, Q, has a trigger, Q¹, a base plate, Q², which is abutted, to prevent lateral movement, by extension A⁷, of the pistol stock, A; a lateral wall, Q³, the outer face of which, when raised, engages the strut L, of the hammer, K, the inward face forming a backing wall against which bear a pawl spring, P, mounted in an arm, A⁸, of the pistol stock, A, and a lift spring S, mounted in a retainer wall, Q⁴, of the trigger member Q.

The detonation strip, T, T¹ is mounted on a stud, A⁹ in the pistol stock A, and passes between tension spring X, mounted on studs A² and A³ in the pistol stock A, and arm A⁸ of said pistol stock, A; thence it passes along the inward face of the wall extension, Q³, of the trigger member Q, underneath the pawl-spring P, and the lift spring, S, and upward to the anvil and exit wall, A⁴ of the pistol stock, or body, A.

The operation of my target practice educator pistol is effected by placing a detonating strip in feeding position as described and shown; aiming at the aiming target and 5 pressing the trigger. This action raises the trigger member lateral wall Q³ against the free end of hammer strut, L, and throws back the hammer, K, against pressure of spring N, from contact with the target rod 10 butt, G, and the anvil A⁴, simultaneously advancing lift spring S, along pawl spring, P, to engage at end of latter the detonating cap there detained and thence bodily lift the free end of the detonating strip until the 15 upper end of trigger member wall Q⁴, presses the detonating strip against anvil wall A⁴, with the advanced explosive cap in position for hammer head K³ to strike it, and the following explosive cap completely 20 covered against back fire by the wall Q⁴ overlapping it. As the hammer, K, recedes, the target rod retracting spring D, rearwardly extends the rod butt, G, to striking position. When the trigger Q¹, is pressed back- 25 ward to its limit, the trigger member wall Q³, rides clear of the hammer strut, L, and the hammer, K, falls by action of its spring, N, the head K, driving outward through the barrel, against the target U, the target rod 30 E, and compressing its retracting spring, D, and hammer head K² striking the anvil wall, A⁴, and detonating the explosive cap thereon. The target rod target U, target block V and hanger frame W, which are sub- 35 ject matter of issued patents, are shown herein with my improved educative pistol because of its relation to this target in the function of aim recording.

Claims:

- 40 1. In an educative toy article of manufacture resembling a firearm, means for aiming at a target, means for marking a target at a point having fixed distance from the line of aim, means for continuous repetition of target marking action without reloading, and means for feeding detonating material and causing an explosive effect coincidently with the action of said target marking means.
- 45 2. In an educative toy article of manufacture resembling a firearm, firearm sighting means for aiming at a target, a member adapted to mark a target and move only in a straight line bearing fixed relation to the line of aim, means for imparting forward movement to said target marking member, means for returning said target marking member to normal position, and means for feeding detonating material and causing an 55 explosive effect coincidently with the forward movement of said target marking member.
- 60 3. In an educative toy article of manufacture resembling a firearm, firearm sighting means for aiming at a target, a target

marking member movable only in a straight line paralleling at fixed distance the line of aim, continuously operable, trigger operated, spring hammer means for repeatedly advancing said target marking member, 70 spring means for automatically retracting said target marking member, and means for feeding detonating material and causing an explosive effect coincidently with the advance of said target marking member. 75

4. In a dummy firearm, a target marking rod, an anvil, a hammer adapted to strike both target marking rod and anvil, a trigger member adapted to engage and elevate said hammer, a tape guiding wall on said trigger member, a stationary pawl engaging said tape guiding wall, and a trigger member mounted pawl engaging said tape guiding wall. 80

5. In a dummy firearm, a target marking rod, an anvil, a hammer adapted to strike, both target marking rod and anvil, a spring retracted trigger member adapted to elevate and release said hammer, a tape guiding wall on said trigger member, a stationarily mounted pawl engaging said tape guiding wall, and a trigger member mounted pawl adapted to engage said stationarily mounted pawl when the trigger member is retracted and engage said tape guiding wall when the trigger member is in operation. 85

6. In a toy firearm, a casing, an anvil, a hammer adapted to strike said anvil, a trigger member adapted to engage, elevate and release said hammer, a tape guiding wall on said trigger member, a pawl mounted on said trigger member which engages with its free end said tape guiding wall on same, and a stationarily mounted pawl which engages with its free end said tape 100 guiding wall on the trigger member. 105

7. In a toy firearm, a casing, an anvil therein, a spring hammer mounted to strike said anvil, a spring retracted trigger member adapted to engage, elevate and release said hammer, a tape guiding wall on said trigger member, a spring pawl mounted on said trigger member to bear against said tape guiding wall and a spring pawl stationarily mounted in relation to said trigger member and bearing against the tape 110 guiding wall of same. 115

8. In a toy firearm, a casing, an anvil therein, a spring hammer mounted therein to strike said anvil and bearing a resilient strut, a spring trigger member mounted therein to engage, elevate and release said hammer by means of its strut, a tape guiding wall on said trigger member, a spring pawl mounted on said trigger member to 120 bear against said tape guiding wall on same, and a spring pawl mounted in the casing 125 to bear against said tape guiding wall on the trigger member.

9. In a toy firearm an oscillatable trig- 130

ger member having a tape guiding wall, a pawl pivotally mounted on the said trigger member and bearing upon said tape guiding wall thereon, and a pawl basically 5 mounted on another member and bearing on said tape guiding wall on said oscillatable trigger member.

10. In a toy firearm, an anvil, a travelling tape guiding wall adapted when advanced 10 to abut its forward end upon the threshold of said anvil, a co-travelling pawl bearing against said wall, and a stationarily mounted pawl bearing against said wall, and means for advancing said wall to said 15 anvil and retracting it therefrom.

11. In a toy firearm, means for gripping between co-movable members the free end of explosive cap tape and advancing said tape

to an anvil across the free end of a detent pawl. 20

12. In a toy firearm an oscillatable trigger member with a tape guiding wall thereon, a pawl pivoted on said member to bear on said wall but separated therefrom when said trigger member is in normal position and 25 having bearing on the said wall when the said trigger member is moved from normal position, and a pawl basically mounted on another member of the said toy firearm and bearing on the said tape guiding wall on the oscillatable trigger member, adapted to interpose between said wall and the pawl mounted on said trigger member when the said trigger member is in normal position. 30

ROBERT E. REARDON.
